UNITED STATES PATENT OFFICE.

ALPHONSE T. CASSIERE, OF LONG BEACH, CALIFORNIA.

MIXING NOZZLE.

Application filed October 18, 1926. Serial No. 142,467.

This invention relates particularly to nozzles in which concrete is mixed and through which the concrete is forced under pressure onto a structure. Heretofore, in nozzles of the above mentioned character it was extremely difficult to properly mix the water with the dry aggregate to obtain a concrete or cement of proper strength.

An object of my invention is to provide a mixing nozzle in which the water is thoroughly mixed with the dry aggregate.

Another object is to provide a nozzle in which the amount of water in the various parts of the nozzle may be regulated to suit the particular conditions.

A further object is to provide a nozzle in which the shape of the stream emitted therefrom can be varied.

Other objects, advantages and features of invention may appear from the accompanying drawing, the subjoined detailed description, the appended claims, or in the operation of the device.

In the drawing—

- 25 Fig. 1 is a side elevation of my nozzle.
Fig. 2 is a sectional view taken on line 2, 2, Fig. 1.
Fig. 3 is an end view.
Fig. 4 is a sectional view taken on line 4, 30 4, Fig. 2.

Referring more particularly to the drawing:

The numeral 1 indicates a hollow annular water ring of my nozzle into which a water pipe 2 extends, the flow of water through said pipe being controlled by the valve 3. A fitting 4 screws into the ring 1 and a flexible hose 5 is suitably secured thereto, said hose conveying the dry aggregate to the nozzle. Vanes 6 are secured in the fitting 4, said vanes extending rearwardly into the hose 5 and forwardly into the nozzle. These vanes may consist of crossed metal plates as shown in Fig. 4, or they may be curved or otherwise formed to suit the particular conditions required. It will be seen that the vanes 6 divide the hose 5 and fitting 4 into a plurality of compartments 7, through which the dry aggregate passes, that is, the stream of aggregate is divided into a plurality of smaller streams which are more readily saturated and mixed with the water as will be hereinafter described.

A plurality of nozzles 8 extend inwardly 55 through the water ring 1, there being one or

more nozzles for each of the compartments 7 formed by the vane 6. The water fed into the ring 1 by the pipe 2, passes through the nozzles 8 into the stream of dry aggregate passing through the nozzle, thoroughly saturating the aggregate and forming a properly mixed concrete.

Each of the nozzles 8 are provided with an adjusting screw 9 by means of which the flow therethrough is controlled. A plug 10 is provided in the ring 1 which may be removed to adjust the nozzles, or if desired the adjusting screw may extend through the ring so that the adjustment may be made from the outside.

To carry the water to the center of the stream passing along the vanes 6, I provide one or more of said vanes with conduits 11, said conduits opening into an annular groove 12 in the fitting 4, and a plurality 75 of ducts 13 extend from the water ring 1 into said groove. Thus it will be seen that a supply of water is maintained at the center of the stream of aggregate passing through the nozzle.

A conical hood 14 screws onto the water ring 1 and the end thereof is provided with a baffle 15 through which a plurality of outlet ports 16 extend. The purpose of the baffle 15 is to cause an eddy or mixing motion within the nozzle which more thoroughly combines the various elements of the concrete. By varying the size and position of the outlet ports 15, I provide any shape desired for the outgoing stream of concrete. If a different shape is desired the hood 14 can readily be removed from the water ring, and a new hood inserted having the number and position of outlet ports required to give the desired effect.

Having described my invention, I claim:

1. A mixing nozzle comprising a water ring, means to conduct water to said ring, a dry aggregate hose extending to said nozzle, and vanes in said dry aggregate hose, and nozzles extending from said water ring, said nozzles extending inwardly in the spaces formed by said vanes.
2. A mixing nozzle comprising a water ring, means to conduct water to said ring, a dry aggregate hose extending to said nozzle, and vanes in said dry aggregate hose, and nozzles extending from said water ring, said nozzles extending inwardly in the spaces formed by said vanes, and means to adjust 105 110

said nozzles to regulate the flow therethrough.

3. A mixing nozzle comprising a water ring, means to conduct water to said ring, a fitting extending into said ring, intersecting vanes in said fitting, said vanes forming passages through which the dry aggregate passes, and nozzles extending inwardly from said water ring, into the spaces between 10 said vanes.

4. A mixing nozzle comprising a water ring, means to conduct water to said ring, a fitting extending into said ring, intersecting vanes in said fitting, said vanes forming passages through which the dry aggregate passes, said vanes having water channels formed therein, said channels opening into said water ring, whereby water is conducted to the center of the flow through 15 said fitting.

5. A mixing nozzle comprising a water ring, means to conduct water to said ring, a fitting extending into said ring, intersecting vanes in said fitting, said vanes forming passages through which the dry aggregate passes, said vanes having water channels formed therein, said channels opening into said water ring, whereby water is conducted to the center of the flow through said fitting, and nozzles extending inwardly from 20

said water ring and means to adjust the flow through said nozzles.

6. A mixing nozzle comprising a water ring, means to conduct water to said ring, and dry aggregate hose extending centrally 35 through said ring, a conical hood threaded onto said ring, a baffle in the end of said hood, said baffle having a plurality of holes extending therethrough.

7. A mixing nozzle comprising a water 40 ring, means to conduct water to said ring, and dry aggregate hose extending centrally through said ring, a conical hood threaded onto said ring, a baffle in the end of said hood, said baffle having a plurality of holes 45 extending therethrough, intersecting vanes in said dry aggregate hose, and nozzles extending inwardly from said water ring.

8. A mixing nozzle comprising a water ring, means to conduct water to said ring, 50 a fitting extending into said ring, intersecting vanes in said fitting, said vanes forming passages through which the dry aggregate passes, and nozzles extending inwardly from said water ring into the spaces between said 55 vanes, and a conical hood secured to said ring and extending forwardly from the ring.

In testimony whereof I affix my signature.

ALPHONSE T. CASSIERE.
